REMOVABLE HINGED ELECTRICAL HEATER

Bernard Altman, Larchmont, and Paul Stiller, Mount Vernon, N.Y., assignors to Still-Man Manufacturing Corp., New York, N.Y., a corporation of New York

Application June 29, 1959, Serial No. 823,454

5 Claims. (Cl. 219—37)

This invention relates to swingably mounted heaters and more particularly to a removable hinged electrical heater for use in ranges, stoves, hot plates, and like electrical equipment.

A hinged heater is useful where it is desired temporarily to change its position on or in an electric range or similar appliance, i.e., swing the heater into a convenient position, either for use or to move it out of the way when not in use, also, as is frequently the case, swing it out of the way when cleaning those parts of the equipment which are adjacent the heater.

An important aspect of this invention relates to the last mentioned convenient feature well suited to electrical ovens in ranges of the type where it is desired to so mount a heater, usually on a horizontal axis, that it can be temporarily swung out of the way (such as to an up-position), in order to clean directly underneath the heater and then let it down to normal service position.

In the manufacture of conventional hinged heaters for electrical ranges and the like, one practice is to provide a hinge means on the rear portion of the heater, which usually requires screw fastenings and related parts, thus involving the use of a screwdriver or other tool for mounting the heater in service position. An inconvenience arises in handling loose screws and other hinge parts, such as a retaining plate to complete the hinged installation when using prior art components.

Such practice lacks simplicity in the hinge structure, due to its several loose parts and the need for tools. Present practice requires a mechanic, when assembling such a heater, especially so when working in the oven portion of a range, to reach back into the depth of the oven to its rear wall and find the screw holes, usually in a shadowed or dark area. At best, a long arm reach is required of the mechanic and, usually, from a stooped position, in order to work in the oven and finally maneuver the several loose parts into service position with a screwdriver or other tool. Altogether, present practice is subject to improvement in order to resolve its problems.

It is a general purpose of this invention to simplify the conventional hinge means for heaters used in electric ranges, and also the mode of installation, as well as provide a hinged heater of less number of parts, which is self-contained, i.e., of unit form (free of loose parts) and which does not require the use of tools when installing it in service position and, in fact, so arranging all movable components in one piece that the hinge can be snap-latched into service position by a simple manual operation.

It is also a purpose to provide a heater which is pivotally mounted (installed) on a support of an electric range, such as its oven wall, by the simple operation of manually plugging the one-piece hinge means of the heater into place—all without the use of screw mountings or equivalents thereof and without tools therefore

2

and, moreover, without the mechanic having to perform the long arm reach heretofore mentioned and in purpose, thereby, reducing the time involved in mounting hinged heaters in the ovens of electric ranges.

The drawings

The accompanying drawings now considered, along with this specification and claimed subject matter, disclose the best mode contemplated in applying the principle of the invention and understanding the problems discovered as well as the new results achieved. Since these teachings may suggest structural changes to others, it is apparent that later modifications may well be equivalents and thus the same in spirit as this invention, as understood by a comparison thereof with the prior art.

Fig. 1 shows one example of the utility of the complete unit—comprising a conventional heating element with this novel latch-in hinge means—mounted in service position on a supporting wall, as in an electric range (such as the back wall of a range oven), a fragment of which is shown schematically.

The following figures are enlarged views (all on the same scale) of the latch-in hinge means built onto (integrated with) a conventional electrical heating element of the sheathed type.

Fig. 2 is a front elevation of the hinge, this view being made on line 2, looking at the hinged heater pivotally mounted on the front surface of the supporting wall at the rear of an electric range, for example its oven.

Fig. 3 is a still view made on the lines 3—3 which are noted in the first two views, showing the hinged heater in its down, i.e., normal service position.

Fig. 4 repeats Fig. 3, except it is an action view showing the heater temporarily lifted upward, so as conveniently to clean underneath thereof, such as the bottom (floor) of the oven.

Fig. 5 is a parts name and numbered action view of the hinged heater unit separated from its supporting wall. The heater is about to be plugged into (or detached from) a pair of spaced hinge slots formed in the range supporting wall.

Note that the legends on Fig. 5 constitute all the part names used in the specification and claims, as well as all the part numbers on the drawings. This presentation makes for uniformity in terminology, thus being helpful in interpreting the disclosure.

The next three are operational views (comprising a series of top-edge views made on the line 6 of Fig. 2), showing the actions involved in mounting the latch-in hinge heater means in service position and removing it therefrom.

Fig. 6 shows the latch-in hinge plugged into the supporting wall, but not yet latched in final position.

Fig. 7 is similar to Fig. 6, except that it shows the hinged heater displaced (shifted) laterally to the right, with a latching (lock-in) space-filler device, of characteristic form and function, snapped into final place for permanently holding the hinge in service and swingable position.

Fig. 8 shows the manner of releasing (manually unlocking) the latch-in hinge, so that the heater may be removed for replacement or repair. Note that one's finger is springing the latch outward and unlocking it. The hinge can now be shifted to the left (back to the Fig. 6 starting position), in order that the unlocked heater be withdrawn from the range.

It is significant that the mode of operation of the hinged heater—as demonstrated in the foregoing views—is carried out without the time consuming and inconvenient

long arm reach heretofore explained in reference to conventional practice. The mechanic assembling this novel hinged heater merely grasps its outer (front) end and inserts (plugs in) the hinge, at its rear end, into the supporting back wall of the electric range.

Although the foregoing description and drawings are believed to explain the invention, the disclosure thereof is amplified by next referring to the part names and numbers throughout all the views, as presented in Fig. 5.

Accordingly, a conventional electric range 10 is shown schematically. It has a back supporting wall 11, in which a rectangular clearance opening 12 is provided, and a pan or floor plate, such as an oven bottom 13. In this example of the invention, the range portion 10 may be assumed to be the oven thereof, for illustrating one of the important applications of this novel heater, so arranged as to make convenient the cleaning of the bottom 13 underneath the heating element, next described.

A conventional heating element 14 of the sheathed or clad type has its rear ends (usually parallel) fixed in a rectangular cover plate 15, slightly larger than the wall opening 12, which is hingedly mounted in a novel manner on the supporting rear wall 11, and covers said opening. Such a heating element 14 is of well known construction. It comprises a tubular metallic sheath, containing an electrical resistance heating coil extending throughout the length thereof, and packed with mineral insulation.

When such a heating element 14 is made for an oven, it may be of rectangular shape (as in Fig. 1), so as to rim or hug the interior perimeter (all four walls) of the oven 10, or it may be U-shaped and thus extend along the front and side walls only of the oven. In other words, the rectangular and U-shape, as well as other shape forms, are not controlling in respect to the hinged heater concept herein.

Note also that when this heating element 14 is made for the top of a range (such as a surface heater), it is usually of spiral or circular form. In this way, it is shaped to conform to the top opening of an electric range, into which the heater is hingedly nested, and onto which a cooking vessel may be placed.

The rear parallel ends of the heating element 14 are fixed in and extend through the cover plate 15 and outward through the clearance opening 12 to the rear of the electric range. An electrical supply circuit wiring (not shown) is connected to the rear ends of the heating element 14, behind the oven or range wall 11, in any well known manner.

A hinge slot 17 is formed in the upright supporting wall 11, just above the upper horizontal edge of the clearance opening 12. In fact, a pair of spaced hinge slots 17 serve to balance the hinge on a horizontal axis for a guided up and down movement (Fig. 4), when the front end of the heater is lifted for underneath cleaning of the pan or oven bottom 13.

A hinge lug 18 extends upward from the top horizontal edge of the cover plate 15 and in the plane of the latter. A hinge ear 19 is also formed integrally with the lug 18, at right angles to the latter, and extends rearward of the upright cover plate 15. A pintle toe 20 projects laterally and horizontally from the hinge ear portion 19, and it is spaced parallel from the rear surface of the cover plate, with adequate clearance for freely receiving the stationary supporting wall 11 for a loose (pivotal) fit of the plate 15 on said wall.

The three hinge portions 18, 19 and 20 form a "hinge-hook" or a pair thereof (Fig. 5) on the swingable cover plate 15. It is noted that the toe 20 and ear 19, these two portions combined, are of a width (parallel to the plate 15) which is about equal to the length of the hinge slot 17, so as to have a slip-fit thereinto. In contrast, the parallel length (width) of the lug portion 18 (like its ear portion 19) is less than the length of the slot 17 in the range wall 11. Accordingly, the two only hinge lug portions 18 and 19 (alone) have a loose sideways fit in the hinge slot 17.

5 A spring arm 22 has one end permanently fastened at 23 adjacent the upper horizontal edge of the cover plate 15. The fastening means 23 may comprise one or more rivets (as shown) or may be spot-welded to the cover plate. This arrangement leaves the other end of the spring arm 22 resiliently free for manual flexure in and out (Fig. 8) in relation to the front surface of the cover plate 15.

10 It is noted that the other or free end of the spring arm 22 is marked 24 on the drawings, thus designating a finger portion 24 which is manually grasped (Fig. 8) to flex the free end outward for releasing a latching means in order that the heater 14 may be removed from the electric range for replacement or repair. The spring arm 22 is disposed (horizontally) close to and parallel with the upper edge of the cover plate 15.

15 It is noted that an upright arm extension 28 is integrally formed on the upper edge of the horizontal spring arm 22 near the flexing-finger portion 24. This arm extension is bent rearward to form a space-filler locking device 29, which parallels and is adjacent to the upright hinge lug 18 and its hinge ear 19. One space-filler 29, in cooperation with one of the hinge-hooks (portions 18, 19 and 20), is sufficient to lock both hinge-hooks into the hinge slot pair 17 formed in the supporting wall 11 of the electric range 10.

20 Having the foregoing structural features in mind, it is thought that the mode of operation of this latch-in hinge heater, with its characteristic hinge-hook and releasable latching space-filler, is clearly understandable. Nevertheless, its mode of operation is next explained.

25 Note that the front end of the heating element 14 may be grasped by hand, and its hinge-hook pair (parts or portions 18, 19 and 20) then inserted or plugged in (Fig. 6) through the hinge slot pair 17. This manual operation causes the rear end edge of the space-filler 29 temporarily to engage or impinge (rest against) the front surface of the supporting wall 11 and, thereby, flex the spring arm 22 outward, thus spring loading (tensioning) it.

30 Next, when the hinged heater is shifted sidewise to the right (Fig. 7), the space-filler 29 (now spring loaded) is caused to snap-latch into that portion of the hinge slot 17 which is not occupied by the hinge ear 19. This action locks the heater in service position onto the supporting wall 11.

35 40 45 50 Such an arrangement of the space-filler means 29 prevents the hinged heater from being reversely shifted sidewise back to the left for its removal, unless the resilient end 24 (finger portion) of the spring arm 22 is manually sprung outwardly (Fig. 8). Doing so withdraws (unlocks) the space-filler 29 from its portion of the hinge slot 17, whereupon the hinged heater units 14 and 15 as a whole may be shifted to the left (Fig. 6) and withdrawn from the supporting wall 11 of the range.

55 60 65 Among other things, this new hinged heater is characterized by the fact that the length of the hinge slot or slots 17 is approximately equal to the combined width (or length paralleling the plate 15) of the hinge ear portion 19 and space-filler 29. Together, their combined horizontal dimension fills the one hinge slot 17 and locks both pintle toes 20 beyond both ends of the two slots for a rocking (hinged) bearing engagement against the rear surface of the range wall 11, thus permitting the front end of the heater 14 to be lifted (Fig. 4) out of the way for cleaning the oven bottom 13.

70 75 Stated in another way, the width of the locking space-filler 29 may equal the length of the pintle toe 20. The dimensional relationship between the hinge slot 17, the hinge-hook (portions 18, 19 and 20), and the spring actuated space-filler 29, taken as a whole, provides a simple automatic plug-in hinge means, having a positive lock-in.

function, which is manually releasable, and free of inconvenient screw-fastening means.

Earlier in this specification, mention was made of a likely U-shaped heating element 14. In such a modified construction, it is noted that each rear end of the then two widely spaced parallel side legs 14 (of such U-shaped heater) would be fitted with a cover plate 15 of small size, one plate for each U leg. Also, two small size clearance openings 12 would be provided (widely spaced apart) in the oven wall 11, together with a hinge slot 17 for each small size clearance opening. Should this equivalent structure be preferred, the spring latching arm 22 would be required on only one of the cover plates of the twin pair thereof.

The simple structure, positive mode of operation and facility of installation are believed to fill a need in the hinged heater art, not available to the trade or suggested in the prior art.

What is claimed is:

1. In a hinged electrical heater, having a cover plate, adapted to close a clearance opening in the wall of an electric range, with hinge means on the rear end of said heater, pivoted in a hinge slot in the range, thus adapting the front end of the heater to be swung from one position to another; that improvement in said hinge means, which is characterized by including all of the movable components of the hinge means on and as a part of said cover plate; said components consisting of a hinge-hook means, of a width less than the length of the hinge slot; and a space-filler, the width of which is about equal to the difference in length between a portion of the hinge-hook and the hinge slot, whereby the space-filler fits into the hinge slot for holding the hinge-hook operatively therein.

2. A hinged electrical heater for an electric range, comprising a sheathed heating element, and parallel rear ends thereon, adapted to extend outward through a clearance opening in a supporting wall of said range; a cover plate fixed on the parallel ends, adapted to rest against the inner surface of the oven wall, to close said clearance opening, and the cover plate having an upper edge disposed horizontally above said clearance opening; a pair of spaced-apart and up-standing hinge lugs, with a hinge ear on each lug, also a hinge pintle toe integrally formed on each hinge ear extending laterally therefrom, all carried on the upper edge of said cover plate, and adapted to be inserted through hinge slots formed in the supporting wall; spring actuated latching means, carried on the plate, for permanently holding the hinge lug means in operative position in the hinge slots, including a manually releasable device operable for removing the heater for replacement or repair.

3. In a hinged electrical heater, having a cover plate, adapted to close a clearance opening in an electric range, with a hinge means on the rear end of said heater, pivoted in a hinge slot provided in the range, thus adapting the front end of the heater to be swung from one position to another; that improvement in said hinge means, which provides for mounting all of the movable components of the hinge means on and as a part of said cover plate; said movable components comprising a hinge-hook means, adapted to swingably fit into said hinge slot of said range, said hinge slot being longer than the width of a portion of the hinge-hook means; and a leaf spring arm, having one end thereof fixed on said cover plate, and its other end flexibly and resiliently free thereof; and a space-filler locking device carried on the free end of the leaf spring arm, the width of which is equal to the difference between the length of said hinge slot and the width of a portion of the hinge-hook means; whereby the space-filler is adapted to snap-latch into that portion of the hinge slot not occupied by the hinge-hook means, to lock the hinged heater in service position.

4. In a hinged electrical heater, having rear end portions fixed in and extending through a cover plate, adapted to

fit over and close a clearance opening in a supporting wall at the rear of an electric range, with a hinge means adapted to be inserted through hinge slot means, thereby swingably mounting the front end of the heater; that improvement in said hinge means, which is characterized by including all of its movable components along one edge of said cover plate; comprising a hinge lug, formed on and in the plane of said cover plate; a hinge ear, extending perpendicular rearwardly from the hinge lug, being narrower than the length of said hinge slot means, and adapted to be inserted through said longer hinge slot means, from the front side of said supporting wall, thereby leaving a locking space at one end of said longer hinge slot means; and a pintle toe extending from the hinge ear, parallel to the supporting wall, and engaging the rear surface of the latter; a spring arm, having one end thereof fixed on said cover plate, its other end being flexibly free thereof, and at rest against the surface of said cover plate; a latch extension, with a space-filler on the flexibly free end of the spring arm, and the space-filler being adapted to project into said locking space, for holding the pintle toe in parallel engagement with the rear surface of said supporting wall.

5. In an electrical heater, conventionally adapted to have its rear end hingedly mounted in an electric range, and its front end manually tilted, wherein a wall of the range has a clearance opening, out through which terminals of the heater rear end extend for connection with a current supply circuit, and wherein the wall also has horizontally separated hinge slots, adapted to receive the hinged heater, and having a cover plate through which the terminals extend and are fixed, the cover plate resting against the inner surface of the wall, and large enough to cover said clearance opening; that improvement in the aforesaid conventional hinge mounting, which comprises spaced hinge lugs carried by said cover plate, extending along an edge thereof, with their upper ends bent rearwardly, forming hinge ears, which are adapted to extend through said separated hinge slots; a lateral pintle toe on each hinge ear, also adapted to extend freely through a said separated hinge slot, and be manually displaced sideways in order to swingably bear against the back surface of said wall, and leave a locking space in at least one of said separated hinge slots; a spring arm, having one end fixed to the front surface of said cover plate, and its other end resiliently free, on which a finger portion is provided, an upright latch extension on the upper edge of said spring arm, and a space-filler on the upper end of the latch extension, adapted to project rearward into an aforesaid locking space; whereby the electrical heater is adapted to be installed in said range, by manually holding the front end of the heater, pushing its hinge ears and pintle toes through said separated hinge slots, which flexes the free end of the spring arm, and then manually shifting the heater laterally, causing the spring arm to snap its space-filler into the locking space, and thus hingedly mounting the heater rear end on said wall; and whereby the heater may be removed from the oven by manually flexing the finger portion of the spring arm outward, which retracts the space-filler from the locking space, and then manually displacing the heater in a lateral direction opposite to that when installing it, as aforesaid, and thereupon withdrawing the heater outward from said range.
